US0D1028039S

(12) **United States Design Patent** (10) **Patent No.:** **US D1,028,039 S**
(45) **Date of Patent:** **** May 21, 2024**

(54) **PART OF NUMERICAL CONTROL
MACHINE TOOL**

(71) Applicant: **Matrix Precision Co., Ltd.**, Hsin-Chu
(TW)

(72) Inventor: **Chi-Hong Lin**, Hsin-Chu (TW)

(73) Assignee: **Matrix Precision Co., Ltd.**, Hsin-chu
(TW)

(**) Term: **15 Years**

(21) Appl. No.: **29/864,178**

(22) Filed: **May 12, 2022**

(51) LOC (14) Cl. **15-09**

(52) U.S. Cl.

USPC **D15/122**

(57) **CLAIM**

The ornamental design for a part of numerical control machine tool, as shown and described.

DESCRIPTION

FIG. 1 is a perspective view of a part of numerical control machine tool showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings represent unclaimed environment only and form no part of claimed design.
